UNITED STATES PATENT OFFICE.

MICHAEL DESPOT, OF DAYTON, OHIO.

FOLDABLE LIFE-PRESERVER.

1,116,393

Specification of Letters Patent.

Patented Nov. 10, 1914.

Application filed July 20, 1914. Serial No. 851,911.

To all whom it may concern:

Be it known that I, MICHAEL DESPOT, a subject of the King of Hungary, residing at Dayton, in the county of Montgomery and State of Ohio, have invented certain new and useful Improvements in Foldable Life-Preservers, of which the following is a specification.

The primary object of this invention is to provide a foldable inflatable means adapted to be secured to a person for preventing drowning, the device being easily folded when not in use.

A further object is to provide a spherical life preserver having a foldable sectional interior frame and whereby upon turning an exterior crank, the device is positioned in its folded compact form.

A still further object is the provision of a spherical float in which a hinged foldable frame-work mounts a pneumatic cover secured thereto and which frame-work and cover are readily folded together by a manually-operated means.

With these general objects in view and others that will appear as the nature of the invention is better understood, the same consists in the novel construction, combination and arrangement of parts to be hereinafter more fully described, illustrated in the accompanying drawings, and then claimed.

In the drawings forming a part of this application and wherein like numerals of reference designate like parts throughout

the several views: Figure 1 is a side elevation of the device. Fig. 2 is a diametrical central sectional view thereof taken longitudinally of the frame mounting shaft. Fig. 3 is a similar sectional view taken transversely of the said shaft. Fig. 4 is an enlarged central sectional detail view of one hinging end portion of the shaft. Fig. 5 is an interior enlarged detail view of the portion of the device adjacent one end of the shaft, the shaft and frame being shown in section. Fig. 6 is an enlarged perspective view of a portion of the foldable frame-work. Fig. 7 is an end elevation of a modified form of the device. Fig. 8 is a perspective view thereof. Fig. 9 is a side elevation of the semi-spherical form of the float employed upon the foot, and, Fig. 10 is a perspective detail view of an end portion of one of the frame members.

Referring more in detail to the drawings, the spherical float as illustrated in Fig. 1

consists of a frame-work formed of semi-circular ribs 10 preferably formed of angle iron and having their ends provided with collars 11 mounted upon the diametrically-positioned shaft 12. One of said ribs 10 has its collar 13 secured to the shaft 12 as by the pin 14 and whereby upon a turning of the shaft 12 by means of the externally-positioned operating crank 15, the rib secured thereto will be rotated while the shaft will revolve within the collars of the unsecured ribs 10 and all of said ribs will be brought into contact with each other in their folded relations. A brace member 16 is centrally pivoted substantially at the center of each of the ribs 10, the ends of the adjacent braces being likewise pivoted together, and thereby equally spacing apart the ribs 10 when unfolded to allow the ribs to fold when desired.

A pneumatic cushion 17 somewhat of the form of a base-ball cover and having an inner chamber 18 adapted for inflation through the nipple 19 is secured over the frame-work and secured to the ribs by the cords 20. The said covering is severed upon a semi-circular line 21 adjacent the position of one of the ribs 10 and is secured together when desired by means of the fastening means 22. With the device closed and ready for use as illustrated in Fig. 1, the same may be folded by loosening the securing members 22 and turning the crank 15, which thereby closes the frame-work and carries the work therewith.

Shoulder straps 23, a belt 24, and leg encircling straps 25 are carried by the cover, and by means of which the float is readily secured upon the back of the wearer. A cord 26 may be secured over the handle 15 when the device is in its unfolded position. The shaft 12 is made water-tight at the points of passing through the cover by means of rings 27 while the water-proof cap 28 is provided over the free projecting end of the shaft.

In the forms of the invention illustrated in Figs. 7, 8 and 9, it will be seen that the floats 29 are semi-spherical in form and the frame-work being similar to that disclosed in the preferred form of construction, it is deemed unnecessary to specifically illustrate the same, it being noted however, that a separate operating crank 30 is provided for the frame-work of each of the floats for the purpose of folding and unfolding the same.

2

while a base 31 is provided for the two floats as illustrated in Fig. 7, and separate bases 32 for each of the floats as illustrated in Figs. 8 and 9. These floats are adapted to 5 be secured to the wearer by means of straps 33, and as illustrated in Fig. 9, the float may be secured to the foot by having a shoe 34 mounted upon the float and provided with a strap 35 for encircling the ankle. This latter form of the device is adapted for use in treading water while the floats illustrated in Figs. 7 and 8 are both adapted to be secured to the body of the wearer.

10 While the forms of the invention herein shown and described are what are believed to be preferable embodiments of the invention, it is nevertheless to be understood that various forms, modifications and arrangements of the parts as shown may be made 15 without departing from the spirit and scope of the invention as claimed.

20 What I claim as new is:—

25 1. A float comprising a shaft, a plurality of semi-circular ribs having their opposite ends journaled upon said shaft and one of said ribs being rigid with said shaft, an inflatable pneumatic cover enveloping said

ribs and secured thereto, foldable spacing braces having their ends pivoted together and being centrally pivoted to said ribs, and 30 means for revolving said shaft.

2. A life preserver comprising a shaft, semi-circular ribs having their ends journaled upon said shaft, opposite collars secured to said shaft, a semi-circular rib secured to said collars, an operating crank at one end of said shaft, equal length braces centrally pivoted to the concaved faces of said ribs and having their ends pivoted together, a hollow cylindrical cover exteriorly secured to said ribs and having said shaft projecting therethrough, water-tight means positioned adjacent the ends of said shaft and engaging said cover, body-attaching straps secured to the exterior of said cover, and securing means positioned between the adjacent edges of the cover.

40 45 In testimony whereof I affix my signature in presence of two witnesses.

MICHAEL DESPOT.
